ROOFING TILE

Julius Kremper, Oakland, Calif.

Application August 28, 1931, Serial No. 559,889

3 Claims. (Cl. 108—10)

The invention relates to improvements in roofing tile.

An object of the invention is to provide tiles of the class described which, in use, provide a particularly watertight and flexible roof.

Another object is to provide for a lateral overlapping of adjacent tiles in such a manner that the fact of such overlapping is concealed.

A further object is to provide for tying the tiles of overlapping courses together and to the roof whereby the forward ends of the tiles may not be lifted by a heavy wind.

Yet another object is to provide for the independent replacement of tiles in a roof thereof, the aforesaid securing means being releasable and the tiles being independently replaceable from the weather side of the roof.

The invention possesses other objects and features of advantage which, with the foregoing, will be set forth or be apparent in the following description of typical embodiments of the invention which are illustrated in the accompanying drawings, in which,

Figure 1 is a fragmentary perspective view showing tiles embodying the invention assembled in a roof.

Figure 2 is a fragmentary outer face view of four interlocked tiles of the roof, a portion of one tile being broken out.

Figure 3 is an enlarged transverse section at 3—3 in Figure 2.

Figure 4 is an enlarged transverse section at 4—4 in Figure 2.

Figure 5 is a fragmentary section at 5—5 in Figure 4.

Figure 6 is a view showing a stack of the tiles viewed from one tile-edge side thereof, portions of certain tiles of the stack being broken away.

Figure 7 is a front end view of the stack of tiles shown in Figure 6.

Figure 8 is a view of the other side of the stack from that shown in Figure 6.

Figure 9 is a fragmentary under face view of a tile.

Figure 10 is an upper face view of another embodiment of the tile.

Figure 11 is an under face view of the tile shown in Figure 10.

Figure 12 is a section at 12—12 in Figure 10.

Figure 13 is a front end view of the tile of Figure 10.

Figure 14 is a view similar to Figure 1 and discloses a tile having a different type of securing means than that shown in the embodiments of Figures 1 to 13 inclusive.

Figure 15 is a fragmentary face view of the tile assembly of Figure 14.

Figure 16 is a section at 16—16 in Figure 15.

Figure 17 is a fragmentary section at the line 17—17 in Figure 16.

Figures 18 and 19 are end and side views respectively of a stack of the tiles disclosed in Figure 14.

Figure 20 is a fragmentary under face view of the tile shown in Figure 14.

Figure 21 is an outer face view of a modification of the tile shown in Figure 14.

Figure 22 is an under face view of the tile shown in Figure 21.

Figure 23 is a section at 23—23 in Figure 21.

Figure 24 is a front end view of the tile in Figure 21.

As particularly illustrated in Figures 1 to 9 inclusive, generally flat tiles 6 are provided for a mutually overlapped engagement at the lateral edges thereof; as shown, side edge portions 7 and 8 of the tiles are reduced from the top and bottom tile faces respectively whereby a portion 8 may overlap a portion 7 of a laterally adjacent and like tile in the same course without thereby increasing the roof thickness thereat. Preferably, and as shown, the complementary faces of the tile portions 7 and 8 are formed to provide grooves 9 and tongues 10 respectively, whereby the grooves 9 provide drainage channels extending solely longitudinally of the tiles and are arranged to receive tongues 10 of a laterally adjacent tile. It is obvious that one or more of the tongues 10 and complementary grooves 9 may be provided in accordance with the degree of lateral seal required; in the present instance there are two of each.

Means are preferably provided for operation as a water baffle at the forward end of the portion 8, and in the present instance said means comprises a cross-wall 11 which provides a flush extension of the forward end face 13 of the tile and extends for the full depth of the tile thereat; it is noted that the cross wall 11 comprises an integral portion of the tile and may be thought of as an unremoved portion of a tile blank. The bottom edge 14 of the cross wall 11 is arranged to closely overlie the opposed tile face portion 15 of the portion 7 of the underlying tile of the next lower course whereby a water baffle is provided opposite the forward ends of the tongues 10 and of the forward ends of the grooves 9 of a laterally adjacent tile when the tongues 10 engage therein. For permitting a disposal of the cross walls 11 in

- the described relation to the forward groove ends, the tile portions 7 terminate at an appropriate distance to the rear of the tile face 13 whereby the tile may be considered to be notched out at 5 the appropriate front corner for the complementary reception of the cross wall 11.
- Baffle means are provided also at the rear end of the tile portion 7, said means comprising a cross-wall 18 providing a flush extension of the 10 rearward end face 19 of the tile which extends upwardly for the full height of the tile thereat. The cross-wall 18 is understood to form a complete closure at the rearward end of the grooves 9 and lies opposite the rearward ends of the 15 tongues 10 of a laterally adjacent and engaged tile. For permitting this disposal of the cross wall 18, the tile is notched out at the rearward end of the tongue portion 8 to receive the cross wall 18 in fitted relation therewith. It is noted that 20 the jointure provided at the cross wall 18 provides a jog in the line of abutment of adjacent and engaged tiles, and that this jointure is arranged to be concealed beneath the forward ends of the tiles of the next higher course thereof.
- 25 Centrally, the tiles 6 are each formed to provide a channel 21 of uniform cross section transversely of the tile, said channel serving to provide the main drainage passage for the tile and preferably extending for substantially the full tile width 30 between the tile portions 7 and 8. Forwardly of the tile, the channel 21 terminates at the face 13. At the rear of the channel 21 a cross wall 22 is provided, said wall extending to the top face of the tile and being aligned with the cross-wall 35 18. In the present embodiment, the channel 21 is of regular trapezoidal section with its shortest base at the bottom. The provision of the channel 21, it is noted, permits a marked reduction 40 of the tile weight and also provides for the reception of a baffle apron 24 provided on each tile for engagement in the channel 21 of the underlying overlapped and mutually aligned tile.
- 45 Preferably, and as shown, the apron 24 depends from the forward end of each tile to provide a continuation of the face 13, and is complementary to the channel space in which it is disposed. In this manner the apron 24 of the tiles of one course are arranged to freely engage the channels 21 of the tiles of the next lower 50 course to permit a variable and adjusted degree of overlap of the courses.
- 55 It will now be noted that a transverse section through the front portion of a tile at a cross wall 11 and apron 24 will have mutually complementary top and bottom lines. Similarly, a section through a rearward portion of the tile at the cross-walls 18 and 22 will also have upper and lower lines which are complementary. Intermediate the tile portions provided with the 60 various baffle walls, the tiles are of uniform section, and the whole relation is such as to permit a particularly compact stacking of tiles for storage or shipment in a minimum space. Furthermore, when the present tiles are stacked in the 65 manner shown in Figures 6 to 8, contacting tiles of a stack are arranged to engage over such a wide area that no special packing is required, with the possible exception of the provision of sheets of paper or the like between the opposed tile 70 faces. This provision for compact stacking is deemed to be a novel and particularly important feature respecting tiles having the high degree of interlock and mutual sealing possessed by the present tiles, since breakage and transportation 75 costs are reduced to a minimum.

Means are provided for securing the tiles to a supporting roof 25, and as shown, said means comprises a provision of an opening 26 in each cross-wall 22 for receiving a fastener member. Preferably, and as shown, the openings 26 are formed as keyhole slots extending longitudinally 5 of the tile and arranged to receive therein a headed fastener means such as the nails 27 particularly shown. The smaller end of the slot 26 is at the rearward end thereof whereby the nail head 28 may retain the tile against an undue lifting from the roof thereof. As particularly 10 shown, the portion of the cross wall 22 adjacent the slot is depressed whereby the fastener head 28 may be disposed beneath the bottom surface of 15 an overlying tile. This means of fastening a tile to an underlying support, it is noted, is arranged to permit the independent removal of a tile from 20 a roof thereof, the nail shank and head fitting loosely for permitting any necessary rocking of the tile during removal or replacement.

The present tiles, it will be noted, may be of glazed or unglazed ceramic ware, or may be formed of any one of a wide variety of concrete mixtures. In any event, the design of the present 25 tiles is seen to be such as to permit their being of minimum weight per unit of area covered by them.

Since in some localities, tile roofs are subject to wind conditions which may tend to lift 30 or shift the tiles of a roof thereof, particularly in case the tiles are of relatively light weight, as in the present instance, means are preferably provided for use in holding down the forward tile ends when and as desired. In the present tile 35 structures, provision is made for tying the forward end of a tile to the rearward end of the underlying tile which it overlaps, said rearward tile end being independently held down by the previously described, or other fastening means. 40

In the embodiment of Figures 1 to 9, provision is made for tying down the forward tile ends by means of a wire or other pliable member 29. To provide for the use of the tying member 29, each tile apron 24 is provided with a pair of central perforations 31 and the tying member 29 is engaged intermediately thereof in the cross-wall 22. As particularly shown, an integral lug 32 extends forwardly from the cross-wall 22 to provide an anchorage for the member 29 which 50 may be either fixedly or loosely engaged in a perforation 33 of the lug.

Preferably, and as particularly brought out in Figure 5, the apron perforations 31 are provided at a distance above the bottom edge of the apron 55 which is greater than the distance of the perforation 33 above the plane of the channel bottom; in this manner the holding-down functioning of the loop formed of the member 29 may be a maximum. It is noted that the tied or twisted 60 ends of the member 29 are exposed in front of the tile face 13; since a tying wire may be of relatively small gauge these exposed fastener ends will not be unduly conspicuous and the knot is exposed for releasing a tile from the top side 65 of the roof.

The tile 41 shown in Figures 10 to 13 inclusive is seen to be generally similar to that of the first described embodiment in respect to the overlap and securing features. The tile 41 differs however from a tile 6 in that the top and bottom surfaces are curved rather than flat, whereby the grooves 42 and tongues 43 of the tile 41 are provided in lateral tile portions having cylindrically convex upper faces, and the central channel 75

44 is cylindrically concave. As in the previously described embodiment, top and bottom base portions of the tile are complementary to provide for a nested stacking of a number of the tiles. 5 The tiles 41 are arranged to be held down by means of wire fasteners 45 for engagement through a front apron 46 of an overlying and like tile, and said fasteners are shown as extending from lugs 47 protruding forwardly from a 10 cross wall 48 at the rear of the channel 44. Baffle means are provided at the rear of the lugs 42 and at the front of tongues 43, said means corresponding to the cross walls 18 and 11 respectively of the previously described embodiment. 15 In Figures 14 to 20 inclusive, tiles 51 are shown having the general construction of the tiles of Figures 10 to 13 as to the sealing overlap provided for adjacent tiles in a roof thereof. The tiles 51 are formed to provide longitudinal grooves 20 52 and tongues 53 at their side edges for a mutual overlapped engagement, and the tile portions providing said grooves and tongues are provided with baffle cross-walls 54 and 55 at their rear and front ends respectively, it being particularly noted that 25 the cross-wall 55 provides part of the planar front face 56 of the tile.

In the present tile, the longitudinal central channel 57 thereof is defined by a cylindrically concave bottom face 58 and overhanging side faces 30 59. The apron 61 at the forward tile end is shaped in a complementary manner to a section of the channel 57 whereby it is arranged for a dove-tailed engagement in the channel for preventing an upward lifting of a forward tile end 35 from the tile which it overlaps in a roof. The channel 57 is of uniform section transversely thereof and terminates at a cross-wall 62 at the rearward end thereof, said cross-wall provided centrally thereof with a bayonet slot 63 for the 40 reception of a nail 64 as a means to secure the rearward end of a tile to a roof 65. The present device for securing a tile against being lifted at its forward end is seen to permit a desired degree of overlap between succeeding courses of the tiles, 45 and to at the same time provide for a completely nested engagement of the tiles to form a stack thereof as shown in Figures 18 and 19.

In the embodiment shown in Figures 21 to 24 inclusive, the provision for a dove-tail interlock 50 by means of the engagement of a front apron 11 in a central drainage channel 72 is disclosed as applied to a flat tile 73 having the interlocking and sealing features of the tiles 6 shown in Figures 1 to 9 inclusive. A plurality of tiles 11 55 may be stacked in the compact manner provided for in the previously described tiles.

From the foregoing description taken in connection with the accompanying drawings, the advantages of the construction and method of operation will be readily understood by those skilled 60

in the art to which the invention appertains, and while I have described the principle of operation, together with certain forms which I now consider to be the best embodiment thereof, I desire to have it understood that the device shown is merely illustrative, and that such changes may be made, when desired, as fall within the scope of the appended claims.

Having thus described my invention, I claim as new and desire to secure by Letters Patent of 10 the United States the following:

1. In a roofing tile, a generally rectangular body formed to have a longitudinal drainage channel intermediate the side edges thereof, a cross-wall closing the rearward end of said channel and 15 provided with a transverse keyhole slot for removably receiving therethrough a headed nail extending from a roof element, an apron depending from the forward portion of said tile to extend into the corresponding said channel of a longitudinally overlapped and similar tile, a lug extending into the channel space from said cross-wall, and a pliable tying element carried by the lug of the underlying tile for tying engagement 20 solely with said apron, said element arranged for tying at the front face of said apron whereby the element is replaceable from the weather side of the roof.

2. In a roofing tile, a generally rectangular body 30 formed to present a longitudinal drainage channel intermediate the side edges thereof, a cross-wall closing the rearward end of said channel, a lug extending into the channel space from said cross-wall, an apron depending from the forward portion of said tile to extend into a corresponding channel of a longitudinally overlapped and similar tile, and a pliable tying element carried by said lug for tying engagement solely with the apron 35 of an overlapping tile thereat to provide a loop 40 substantially parallel to the tile plane.

3. In a roofing tile, a generally rectangular body 45 formed to present a longitudinal drainage channel intermediate the side edges thereof, a cross-wall closing the rearward end of said channel and provided with a transverse keyhole slot centrally thereof for removably receiving therethrough a headed nail extending from an underlying roof element, an apron depending from the forward portion of said tile to extend into the corresponding said channel of a longitudinally overlapped and similar tile and provided with a pair 50 of openings centrally therethrough and directed longitudinally of the tile, a lug extending forwardly from said cross-wall centrally thereof, and 55 a pliable tying element carried by the lug of the underlying tile for extension through said apron openings for tying into a loop for mutually securing the tiles thereat.

JULIUS KREMPER. 60
